CHICAGO, ILLINOIS

METALLIC LAUNDRY NET

Application filed March 8, 1928. Serial No. 260,218.

Our invention relates to improvements in laundry devices, and more particularly to those laundry devices employed in connection with the washing, rinsing, bluing, bleaching, and other processes incident to the preparation of laundry.

The general object of our invention is to provide means adapted to effect a substantial saving of equipment, time and labor in laundries, thereby greatly increasing the efficiency of establishments engaged in this line of work.

A more particular object of our invention is to provide a novel, laundry net of flexible, durable metallic construction, incorrodible to the acids and alkalies used and non-absorbent to other chemicals employed in laundry work, while adapted to give service over an indefinite period.

In modern laundry practice, it is customary to place the garments and other articles of each individual in a separate fabric net of rather heavy coarse texture, each net having a numbered tag thereon for the identification of each individual bunch of articles to be laundered. These articles are retained in their individual net while in the power operated washing machines during the processes of washing, rinsing, bluing, bleaching or any of the other processes employed. As is well known, a considerable percentage of the soap, alkali, and other solutions used in the above mentioned processes are absorbed directly into the fabric net containers. By repeated tests, it is found the average cotton fabric laundry net now in use and weighing approximately fourteen ounces, absorbs two and one-half times its own weight of the solutions employed. In other words, a fourteen ounce laundry net absorbs approximately 35 ounces of solution. The immediate result of this great absorption of solution is a quick pollution of the rinsing water into which the washed articles are immediately immersed after washing. Seven rinsings are generally

employed to free the washed articles from the washing solutions.

It is, of course, understood that during the washing process the nets with the articles therein are placed in a large drum or vat partially filled with a soap solution and the drum rotated, by the suitable application of power, two or three times in one direction, then immediately followed by an equal number of revolutions in the opposite direction, this cycle being repeated until the desired cleansing is obtained. The nets during the rotation of the drum are tumbling about therein in the solution, it being observed that a mechanical squeezing and kneading of the garment is effected by the falls and rebounds thereof, which assists in drawing in, expelling and communicating movement to the solution into, around and through the net and its contents. This same procedure is used in connection with the other processes preparatory to drying of the articles in the centrifugal machine.

The method above indicated is that now employed in modern commercial laundries, being esenstially mechanical and thoroughly efficient. However, in actual practice, it is found the fabric nets by constant immersion in the various solutions used are subject to rapid deterioration, thus soon resulting in rupture and disintegration of the net. As this comparatively early breakdown or bursting of the net is likely to occur to other nets of the same age and usage at about the same time, considerable inconvenience is caused by the intermingling of diverse articles belonging to different individuals, thereby occasioning great confusion and quite often loss of some of the articles through inability to identify the owner. In other respects, the textile net heretofore in use did not permit as free a flow of the solution therethrough as would be desired, necessitating a longer period of immersion in the drum. Enumerating, therefore, briefly the

disadvantages of the present textile net in use for the purpose of setting forth the superior method and construction now to be defined in detail, it may be said the defects of the textile net are (1) the absorption of solutions, (2) the impedance of flow of the solutions within the bags, (3) early disintegration of the bags, (4) time required to complete the several processes.

- 10 By means of our invention now to be described, we have succeeded in overcoming the above disadvantages in addition to which we secure important mechanical advantages in that a freer flow of solution is achieved 15 through the more open interstices of our metallic mesh; a more thorough kneading effect of the garments within our net is obtained by reason of its compactness and freer transmission of the movements arising during 20 its tumblings in the drum, while being incorrodible and non-absorbent to the solutions used, disintegration from these causes is obviated.

25 Describing then, our invention in connection with the accompanying drawings,

Figure 1 is a perspective view of a bag embodying our invention.

Figure 2 is an enlarged detail view showing the method of construction of the flexible 30 metallic net employed in our device.

Figure 3 is a fragmentary sectional view of the net construction.

With more particular reference to the drawings wherein similar characters of reference indicate corresponding parts in the several views, A designates a net formed of metal rings 11, which, as shown in Figure 2 are interlaced in a manner whereby each of the rings are passed through three other similar rings, this method providing a mesh of the utmost flexibility with a comparatively large orifice for the ingress and egress of the solutions in which the bag with its contents is immersed. The ends of each of the rings 40 or links 11 are smoothly soldered or brazed together whereby an endless non-abrasive metallic fabrication is obtained. As a closure for the net, we provide what is commonly termed a blanket safety pin 12 which 45 serves to hold the mouth of the net closed during manipulation thereof while the clasp 13 permits the detachment of the safety pin when the net is to be emptied. As a means of identification, a reference character may 50 be placed on the joint 14 of the pin.

We have found by experience nearly all of the so-called familiar metals to be unsuited for the purpose of a net to be employed as a container for articles during the laundry 55 process above indicated, but as an important feature of our invention, we have ascertained by experiment an alloy termed "Monel" metal to admirably adapt itself to the functions required for use in laundry work. This metal 60 is practically incorrodible to the normal solu-

tions employed in laundry work, which for the most part are alkaline and in some cases acidulous, the latter being employed to counteract and neutralize the presence of alkali remaining in the washed garments. The soap and bluing solutions, of course, are not as injurious in their effects as the alkali and acids indicated, nevertheless the bleaching process again is a powerful caustic and destructive agency to the textile nets heretofore employed, which, unlike the garments washed, were almost continuously subjected to the action of the solutions. Particular attention is called to the comparatively large interstices of our metallic net mesh which provide for a much freer flow of solution than was possible to the textile nets used.

70 We have found in actual practice that the washing process may be more quickly accomplished by the use of these nets by reason of the more free flow of solution into and out of the bags than was possible to the textile nets heretofore employed; in addition to which it is found that at least one or two of the rinsings required can be dispensed with owing to the same freer flow of the water over the garments through the unobstructed meshes of our metallic container.

75 A further saving of time is effected in the other processes to which the washed and rinsed articles are now subjected, and since the articles are laundered with more mechanical and less chemical treatment, a longer life to the articles so treated is secured. As a consequence of our method and the means employed, a substantial saving of time, labor, consumption of power and material is clearly demonstrable.

80 We are aware of the use of metallic meshes as hampers and carriers of heterogeneous species of merchandise, but the use of a metallic mesh of the herein detailed description we believe to be new in the laundry art.

85 While we have described the nature of our invention and the structural details thereof with particularity, it will be understood that minor variations and changes may be made therein without departing from the spirit of our invention. It will be obvious for instance that a larger or smaller metallic mesh may be 90 substituted for that indicated, or that for example the configuration of the rings could be made oval or other desired shape.

95 What we claim as new and desire to secure by Letters Patent is:

1. A laundry net for holding fabric articles immersed within a liquid to be mechanically agitated for the purpose of treating the articles contained therein, comprising a metallic meshing constructed of inter-laced 100 rings, said rings having complete continuity and smoothness throughout, and composed of metal having non-corrosive properties.

2. A laundry net for holding fabric articles immersed within a liquid to be mechanically 105

agitated for the purpose of treating the articles contained therein, comprising a metallic meshing constructed of inter-laced rings, said rings having complete continuity and smoothness throughout, each of said rings arranged to engage three adjacent rings in the body of the meshing, and said rings composed of metal having non-corrosive properties.

In testimony whereof we have signed our names to this specification.

HELGE A. GILBERTSON.
